UNITED STATES PATENT OFFICE.

ERNST WAGNER, OF REUTLINGEN, GERMANY.

WIRE TWISTING AND WEAVING MACHINE.

1,096,080.

Specification of Letters Patent. Patented May 12, 1914.

Application filed August 28, 1912. Serial No. 717,599.

To all whom it may concern:

Be it known that I, ERNST WAGNER, a citizen of the Empire of Germany, and residing at Reutlingen, Germany, have invented 5 certain new and useful Improvements in Wire Twisting and Weaving Machines, of which the following is a specification.

My invention relates to that type of wire twisting and weaving machine, for making 10 wire netting of quadrangular mesh in which lengths of wire are given a zigzag shape or the form of a flat spiral by means of a coiling worm surrounding a coiling knife, and are then interlinked or interlaced with the 15 finished netting by the zigzag wire being threaded through the last row of mesh of the finished netting.

Important objects of my invention are to 20 provide firstly, improved controlling mechanism of the driving members of the individual operative members; secondly, improved guide means for the zigzag wire during the interlacing operation; thirdly, improved mechanism for closing the meshes 25 at the edge of the netting; fourthly, an improved device for winding up the netting, and fifthly, other improved details of construction described hereinafter.

To these ends my invention consists in 30 the combination of parts described herein- after and embodied in the claims.

My invention is represented by way of example in the accompanying drawings, wherein:

Figures 1 and 2 are front elevation and 35 top plan view, respectively, showing a wire twisting and weaving machine embodying my invention, some unimportant parts having been omitted; Figs. 3, 3' and 4 show, on 40 an enlarged scale, the regulating and driving device in end elevation in a vertical section taken on line 3—3 in Fig. 2 and in a sectional front elevation respectively; Fig. 5 is a vertical section through the regulating 45 mechanism taken on the line 5—5 in Fig. 4; Figs. 6 and 7 are front elevation and end elevation, respectively, showing the gripper device and guide channel; Fig. 8 is a front elevation showing the device for bending 50 over the ends of the wire; Figs. 9, 10, and 11, show some parts of the regulating device in different positions; Figs. 12, 13, and 14 are vertical section, top plan view, and front elevation partly in section, respectively, showing the cutting device; Figs. 15 55 and 16 are end elevation and top plan view, respectively, showing the winding device;

Fig. 17 is a front elevation, partly in section, showing the coiling knife and coiling worm; and Fig. 18 is a vertical section 60 showing a modification of the device for guiding the zigzag wire.

Referring to the drawings, the main driving shaft 2 mounted in suitable bearings on the frame 1 of the machine drives the shaft 65 12 of the coiling knife 14 through the medium of the spur gears 6, 8 and 11, 122 and the countershaft 7, and the shaft 19 through the medium of the spur gears 6, 10 and 17, 18 and the countershaft 9. This 70 shaft 19 drives the blades 63, 64 for cutting the wire by means of an eccentric 65 (Figs. 2, 12 and 13); it drives also, by spur gears 24 and 54 the shaft 52 (Figs. 2 and 3), which actuates by means of cams 109 (Fig. 75 2), the apparatus for bending back the wire ends projecting at the edges of the finished netting (see Figs. 7 and 8); the shaft 52 drives also, by means of a chain gear 55, 56, 57, (Figs. 2 and 3) a shaft 51 which controls, by means of a cam 91 (Figs. 1, 6 and 7) a device for holding the netting in the desired position at the subsequent working cycles (see the hooks 84, Figs. 6 and 7). The shaft 51 has also the function 80 to shift, by means of a cam 77 (Fig. 1), the coiling and interlacing tool 14, 15, shown in Fig. 17, lengthwise of the machine alternately in the one and then the other direction with the subsequent 85 working cycles, and it influences also, by means of a cam 50 (Fig. 3), the regulating device. The shaft 19 actuates also, by means of a cam 139 (Figs. 15 and 16), the winding-up mechanism. The shaft 12 can be disconnected from the main shaft 2 by means of the clutch 13 (Fig. 2); and the shaft 19 can be disconnected therefrom by means of the clutch 20. The one or the other slideable clutch, which are both under the influence of 90 springs or the like tending to throw them into gear, is thrown out of gear by the action of wedge-shaped ends of the three-armed controlling lever 21 (Fig. 3) coacting with corresponding slanting faces on the clutches. 95 When this three-armed lever is rocked to the left against the action of the spring 23 out of the position, not shown, in which it holds the clutch 13 of the shaft 12 disconnected, the clutch 20 of the shaft 19 being engaged, 100 and into the position shown in Fig. 3, it holds the clutch 20 of the shaft 19 disconnected, the clutch 13 being engaged; this 105 rocking motion is caused by the cam 24

(Fig. 3) fast on the shaft 19, which cam acts on the antifriction roller 25 carried by the third arm 21" of the controlling lever 21, and it is securely held in this position by the locking lever 26 (Figs. 1 and 4) acting as a catch owing to the end of the arm 21' of the lever 21 projecting through an aperture (Fig. 4) in the front wall of the framework into a notch or recess 26' in the lever 26 pulled to the left by the spring 28.

The locking lever 26 may be released for enabling the lever 21 to rock back into the first position, not shown, into which it tends to move under the action of the spring 23, only when the coiling-knife shaft 12 has rotated as many revolutions as the netting is to have meshes in width. The regulating mechanism shown in Fig. 5 which brings about the release of the locking lever 26 through the medium of the connecting-rod 29 (Figs. 1, 2 and 4) is adjustable in such manner that the release takes place earlier or later according in each instance to the number of meshes required. This regulating mechanism is constructed as follows:

The axle 39 carried by the bearing 34, 35 is coupled with the coiling-knife shaft 12 through the medium of speeding down gearing which, in the illustrative embodiment, is formed as pawl and ratchet mechanism. The ratchet 128 is free to rotate on a sleeve-like extension of the bearing 34. The lever 33 is free to rock about the hub of this ratchet, and this lever carries not only the pawl 129 which engages in the ratchet 128 but also an antifriction roller which projects into the cam-way of the ring 32 fast on the end of the shaft 12. The ratchet-wheel 128 drives the axle 39 through the medium of a claw clutch 36, 37, 38. When the shaft 19 is stationary and the shaft 12 rotates the axle 39 is rotated slowly through the medium of the pawl and ratchet gearing, and the cord 44 carrying a weight 45 is wound up around the pulley 43. When the axle 39 has rotated about half a revolution counterclockwise from the position shown in Fig. 1, the lug or stop 30 carried by the disk 31 abuts against the outer end of the connecting-rod 29 pivoted to the locking lever 26.

This lever 26 is thereby disengaged and the three-armed lever 21 can rock clockwise under the influence of the spring 23, whereby the clutch 13 of the shaft 12 is disengaged and the clutch 20 of the shaft 19 at once closes under the action of its spring. The shaft 19 now rotates one single revolution counter-clockwise, and actuates the above-mentioned operative devices connected with it. At the beginning of the rotation of this shaft 19 it rocks the angle lever 47 (Fig. 3) by means of the cam 46, and the shorter arm of this lever disconnects the claw clutch 36, 37, 38 of the regulating mechanism. In this manner the axle 39 is

temporarily disconnected from the now stationary shaft 12 and can rotate back into its initial normal position under the action of the weight 45. The toothed disk 31 (Fig. 5) carrying the stop 30 which acts on the rod 29 is operatively connected with the axle by a toothed clutch member 41 in similar manner as the ratchet 128, and after the nut 42 has been released can be coupled in various positions with the disk 40 keyed on the axle. By rotating the disk 31 clockwise relatively to the disk 40 the machine is adjusted for making greater widths of netting and by rotating it counterclockwise for smaller widths. In order to facilitate this adjustment the edge of the disk 31 may be provided with graduations, as shown in Figs. 2 and 3, which move under a pointer attached to the framework.

For the reason stated hereinafter the shaft 12 must always rotate one revolution more at the second, fourth and sixth interlacing operation than at the first, third, fifth, etc. To this end, I form the free end of the rod 29 stepped, as shown in Figs. 9 to 11, and it is alternately raised and lowered in such manner by means of the two-armed lever 58, suitably actuated by driving gear 50, 51, 52 (Fig. 3) that at the end of each interlacing operation first the one face and then the other is located in the path of the stop 30. The gearing 57, 56, 55, 52 of the shaft 51 is constructed in such manner that while the shaft 19 rotates one revolution, the shaft 51 rotates half a revolution, the short arm of the lever 58 bearing against the low part of the cam 50 during one interlacing operation and against the projecting part thereof during the next.

In the illustrative embodiment shown in Figs. 9 to 11 the rod 29 has a folding, hinged end portion 60' whose abutment faces project beyond the faces of the end 60 of the rod 29; when the end portion 60' is folded downward the lever 26 is reversed, i. e. disengaged, earlier than when the said portion is lifted up; so that in the former case the shaft 12 rotates one revolution or half a revolution less than in the latter case.

The wire netting which runs from the place where it is made over the guide 83 (Figs. 1, 6, 7, and 15) to the winding device is kept in such a position by the hooks 85 (Figs. 6 and 7) engaging in the last row of meshes but one that the last row of meshes depend to near the bottom of the guide channel 16. The wire for forming the new meshes is bent zigzag by the coiling knife 14 rotating within the coiling worm 15 (Fig. 17) and is moved spirally into the channel 16 arranged coaxially with the coiling knife, so that the front end of the zigzag wire interlaces with the last meshes of the netting located in the channel. This operation is represented in Fig. 18; for the

sake of clearness the new zigzag wire 126 being inserted is shown in solid black. When the beginning of the new zigzag wire has arrived at the outside edge of the netting the coiling knife is automatically stopped in the manner described above, and the shaft 19 now rotates. This shaft then operates the cutting device shown in Figs. 2, 12, 13 and 14 which cuts off the zigzag wire at the front edge of the netting. This cutting device substantially consists of two slides 67 and 75 mounted to slide from both sides toward the wire; the former slide carries two blades 63, and the latter one blade 64 which when cutting enters between the two blades 63. This cutting device is driven through the medium of the eccentric rod 66 and the eccentric 65 by the shaft 19, the slide 67 being directly driven by the rod 69, and the slide 75 through the medium of the two-armed lever 68, the connecting-rod 71 and the lever 72 in a direction opposite to that in which the slide 67 is driven. Further, when the shaft 19 rotates it drives, through the medium of the shaft 52, the devices for closing the meshes at the edge of the netting shown in Figs. 7 and 8. As shown in Fig. 1, two of such devices are provided, the one of which closes the meshes on the right-hand, and the other the meshes on the left hand of the netting. These devices are constructed as follows: The puppet 100 is slidable on the bed-plate 1 of the machine and can be moved by rotating the hand-wheel 102 shown in Figs. 1 and 2. A slide 112 is slidable longitudinally on the top of this puppet. In the end of this slide facing the netting is mounted the forked head 108 in whose 40 prongs are journaled the members for bending the ends of the wire, *i. e.* the grooved rollers 114. The slide 112 is moved toward and away from the netting by means of a cam 109, fast on the shaft 52, and the two-armed lever 110. At the same time as the slide 112 is driven forward a slide 99 movable vertically along the end of the puppet is shifted upward through the medium of the angle lever 101 by means of a second cam 103, fast on the shaft 52, in such manner that the mandrel 96 carried by the horizontal arm 97 of this slide enters into that mesh at the edge of the netting whose projecting ends are to be bent over. When the 55 slide 112 moves forward the shoulder 106 on its bottom face abuts against the pin 104 movable vertically in a second horizontal arm 105 of the slide 99. The angle-lever carrying the mandrel 96 is hereby rocked right-handedly so that its hook-shaped end 111 engages the mesh and presses it against the bending tool, *i. e.* the grooved rollers 114. On the forked head 108 carrying the 60 said bending tool is a pin 116 which is directed horizontally to the rear (Fig. 7) and

passes through a slotted guide 115 rigidly attached to the puppet. When the head 108 moves forward toward the netting the ends of the wire are not only bent round owing to their entering into the grooves of the rotating rollers 114, but also are twisted a little in consequence of the rotation which is imparted to the head when moving forward owing to the pin 116 being guided in the slotted guide 115. After the wire has been 75 cut off the netting can move forward the distance of half a diagonal of a mesh. In order to enable this the shaft 86 carrying the hooks or grippers 84, 85 must be rotated counterclockwise in such manner that 80 the hooks 85 may move out of the meshes in which they are engaging, and that the hooks 84, arranged staggered half a diagonal of a mesh longitudinally relatively to the hooks 85, may enter into the next 85 lower row of meshes. This rocking motion is imparted to the shaft 86 by the shaft 51 which, in turn, as mentioned above, is driven in such manner that it rotates half a revolution during one revolution of the shaft 90 19. To this end, the shaft 51 carries a cam 91 against the periphery of which the ends of the two lower arms of the three-armed lever 93 bear at approximately diametrically opposite points. The end of the top arm 92 95 of this lever engages in a fork 94 fast on the shaft 86. During one interlacing operation the end of the one, and during the next operation the end of the other of the two lower arms of the lever 93 bears on the 100 projecting part of the cam 91, so that the hooks 85 and 84 alternately engage in the netting. In order that the new zigzag wire can be correctly interlaced into the last zigzag wire now forming the last row of 105 meshes of the finished netting, the former must be shifted longitudinally relatively to the latter, as shown in Fig. 18, a distance equal to the half of the diagonal of a mesh, so that when interlacing a wire the top 110 points of the former zigzag fall into the bottom parts of the last zigzag. Therefore, before a new zigzag wire can be interlaced with the end meshes of the netting it must be moved away from the finished netting a 115 distance equal to half the diagonal of a mesh. To this end, the vise 81 having the two jaws 76 holding the coiling worm 15 is mounted to slide longitudinally on the bed 120 1 of the machine, this motion being imparted to it by the shaft 51 through the medium of a cam 78 (Fig. 1) on this shaft, a two-armed lever 77, a connecting-rod 79, a two-armed lever 80 and a rod 82. In order to enable the coiling knife 14 rotating in 125 the coiling worm 15 to participate in the longitudinal motion of the latter, the coiling knife is connected with its shaft 12 through the medium of a sleeve 130 (Fig. 17) which can shift longitudinally on the 130

end of the shaft but is rotated by the feather 131. An antifriction roller 133, journaled in the end of an arm 132 rigidly attached to the vise 81, engages in a groove 134 in the sleeve 130. When the new zigzag wire 126 which is moved in the above-described manner half a diagonal of a mesh away from the netting, as illustrated in Fig. 18, has been interlaced with the netting and cut off, the coiling worm and the knife are moved toward the netting half a diagonal of a mesh, and the following zigzag wire is thereby shifted the requisite distance relatively to the zigzag wire 126 now forming the last row of meshes. Of course, when inserting the zigzag wire 126 moved away half a diagonal into the netting, in order that the beginning of the wire may certainly pass to the outside edge of the netting the coiling knife must rotate half a revolution more than during the previous and the following interlacing operation. This requirement is met by the above-described formation of the end 60 of the rod 29 in steps which is rocked by the lever 58. The device for winding up the finished netting is constructed as follows:—The finished netting runs along the guide 83 to the winding roller 135 (Figs. 15 and 16) carried by two floor-frames 149 at the rear of the machine. On the journal of this roller projecting out of the bearing of the front floor-frame 149 is keyed a ratchet 150, in which engages a spring-pressed click 152 journaled on the floor-frame and preventing the roller rotating backward; on the same journal is fulcrumed a two-armed lever 136, which is connected with a pinion 140, and whose top end carries a pawl 151 likewise engaging in the ratchet; this lever has a rocking motion imparted to it at every revolution of the shaft 19 by a cam 139 on the shaft 19 through the medium of a second two-armed lever 138 and a connecting-rod 137. When the cam 139 rotates counterclockwise, the two-armed levers 138 and 136 are rocked to the left, the pawl 151 slides over the teeth of the ratchet 150 and the lever 143, which is keyed on the pivot of the gear 141 and carries the weight 144, is simultaneously lifted by the pinion 140 in mesh with the gear 141. When the projection of the cam 139 has passed the antifriction roller 142 carried by the top end of the lever 138, this lever is rocked back by the action of the weighted lever 143, and the pawl 151 rotates the ratchet 150 and with it the roller 135 until the netting is stretched taut. Obviously, the length of netting wound up during each oscillation of the levers cannot amount to more than half a diagonal of a mesh. The greater the diameter of the roll of netting becomes owing to the continued winding up, the less will be the return rocking motion of the levers.

At the rear of the roller 135 for the netting is located the roller 146 which is carried by two arms 147 and is connected by a rod 145 with the weight 144 movable along the lever 143.

Referring again to Fig. 18, in contradistinction to the guide means shown in Figs. 6 and 7 comprising the guide channel, 16, 123, in which the zigzag wire is completely hidden from view while it is being interlaced, this Fig. 18 shows modified guide means for guiding the zigzag wire while it is being interlaced, in which the interlacing operation can be readily observed. These modified means substantially consist of a ring 125, preferably approximately the length of one diagonal of a mesh, into which the finished netting depends through a slit in the same manner as in the channel according to Fig. 7, and which is fed forward synchronously with the front end of the zigzag wire by means of an endless screw 127.

In the form shown in Figs. 6 and 7 both the hooks 84, 85 and also the guide channel 16, 16, 123 are adjustable for various widths of mesh. For large meshes the walls 16, 16 of the channel are drawn apart and the two-part cover 123 is drawn upward; the hooks 84, 85 are also pulled upward after their screws 90 have been loosened. The hooks are adjusted longitudinally as follows:—After loosening the screws 88 the pairs of the hooks are moved apart corresponding to the larger mesh, and then after loosening the screws 89 each pair of hooks is adjusted in such manner that a hook 84 is half a diagonal of a mesh away from a hook 85.

It is to be understood that the above-described constructions may be substituted by mechanical equivalents without departing from the scope of the invention. For example, instead of the two-armed lever 21 which brings about the reversal of the clutches 13, 20, any other suitably formed member, *e. g.* a slideable member, may be employed. Also, instead of the axle 39 being uncoupled from the shaft 12 by the claw-clutch 36, 37, this may be brought about in other suitable manner, *i.e. g.* by lifting the pawl 129. Further, instead of the axle 39 being driven by the pawl and ratchet mechanism 128, 129 it may be driven by any other suitable speeding-down gearing, *e. g.* worm gear. Again, instead of the rollers 114 for bending over the ends of the wires being arranged rotatable in the head 108 of the tool, they may be mounted fixedly thereon. Lastly, when the tool-head 108 moves forward, instead of turning a little corresponding to the bend of its guide slot, it may rotate a complete revolution, in which event the ends of the wires will be twisted.

I claim:

1. In a machine for manufacturing wire

netting, a main driving shaft, a coiling shaft, a second working shaft, coupling means for connecting both the latter shafts with said main shaft, a controlling member 5 adapted to hold alternately the one or the other of said coupling means disengaged, a cam on the second shaft adapted to move the controlling member into that position in which it holds the coupling means of this 10 shaft disengaged, a spring-actuated locking member adapted to lock the controlling member in this position, and mechanism for regulating the number of revolutions to be made by the coiling shaft, said mechanism 15 being operatively connected with this shaft and adapted to release the controlling member from said locking member.

2. In a machine for manufacturing wire netting, a main driving shaft, a coiling 20 shaft, a second working shaft, change-over coupling means adapted alternately to hold the one or the other of the latter shafts connected with said main shaft, mechanism for regulating the number of revolutions to be 25 made by the coiling shaft, said mechanism being operatively connected with this shaft, and means actuated by the second shaft for momentarily disconnecting this mechanism from its operative connection with the coiling 30 shaft.

3. In a machine for manufacturing wire netting, a main driving shaft, a coiling shaft, a second working shaft, coupling means for connecting both the latter shafts 35 with said main shaft, a controlling member adapted alternately to hold the one or the other of said coupling means disengaged, a spring-actuated member adapted to lock the controlling member in one position, regulating 40 mechanism for regulating the number of revolutions to be made by the coiling shaft, and a bar for transmitting motion from the regulating mechanism to the locking member, said bar being influenced by a 45 shaft in operative connection with the second shaft in such manner that at every other working stage the coiling shaft is allowed to make one revolution more than at the preceding and following stages.

4. In a machine for manufacturing wire netting, a main driving shaft, a coiling shaft, a second working shaft, coupling means for connecting both the latter shafts with said main shaft, a controlling member 55 adapted alternately to hold the one or the other of said couplings disconnected, mechanism for regulating the number of revolutions to be made by the coiling shaft, said mechanism being operatively connected with 60 this shaft, a spring-actuated member adapted to lock said controlling member in one position, and a bar linked to this member and carried by a lever actuated by a cam on

a shaft operatively connected with the second shaft, the free end of said bar lying 65 in the path of a lug on a member of the regulating mechanism and having two faces, the one or the other of which is alternately engaged by said lug.

5. In a machine for manufacturing wire 70 netting, a main driving shaft, a coiling shaft, a second working shaft, change-over coupling means adapted to hold alternately the one or the other of the latter shafts connected with said main shaft, two supports 75 arranged at the two sides of the netting, a slide having a forked head slidable on the top of each support, means for moving the slides toward and away from the edges of the netting, and two grooved rollers 80 journaled between the prongs of each forked head for bending back a pair of converging wire ends at the edge of the netting.

6. In a machine for manufacturing wire 85 netting, a main driving shaft, a coiling shaft, a second working shaft, change-over coupling means adapted to hold alternately the one or the other of the latter shafts connected with said main shaft, two supports 90 arranged at the two sides of the netting, a slide having a forked head slidable on the top of each support, a curved slotted guide mounted on each support, a pin on each head projecting into the slotted guide on each support, means for moving the 95 slides toward and away from the edges of the netting, and two grooved rollers journaled between the prongs of each forked head for bending and twisting a pair of converging wire ends at the edge of the netting. 100

7. In a machine for manufacturing wire netting, a main driving shaft, a coiling shaft, a second working shaft, change-over coupling means adapted to hold alternately 105 the one or the other shaft connected with said main driving shaft, two supports arranged at the two sides of the netting, a slide on the top of each support, a tool carried by the slide for bending back a pair 110 of converging wire ends, a second slide movable vertically on each support, means for moving both slides toward and away from the edge of the netting, and a finger fulcrumed on the second slide and adapted to 115 enter a mesh of the netting opposite the same, the bottom face of the former slide comprising a cam surface for actuating said finger and rocking the same when the said slides move toward the netting. 120

In testimony whereof, I affix my signature in the presence of two witnesses.

ERNST WAGNER.
